UNITED STATES PATENT OFFICE.

SIMON W. WARDWELL, OF PROVIDENCE, RHODE ISLAND.

BRAIDING-MACHINE.

1,073,308.

Specification of Letters Patent. Patented Sept. 16, 1913.

Application filed January 19, 1911. Serial No. 603,530.

To all whom it may concern:

Be it known that I, SIMON W. WARDWELL, a citizen of the United States, residing at Providence, in the county of Providence and State of Rhode Island, have invented certain new and useful Improvements in Braiding-Machines, of which the following is a specification.

My invention relates to braiding-machines and especially to the devices for actuating the stopping-mechanism to control the operation of the machine. My new device is particularly adapted for use on machines such as that shown and described in my Patent No. 1,032,870, granted July 16, 1912, in which the fabric is braided from a plurality of yarn supplies or cops carried in two tiers rotating in opposite directions about a common axis.

My invention consists of improvements in the devices for operating the stopping-mechanism when a yarn breaks or the supply becomes exhausted and also provides means for stopping the machine when the yarn becomes snarled or tangled or is otherwise prevented from delivering freely from the cop.

The invention is fully described in the following specification, illustrated by the accompanying drawings, in which:

Figure 1 is a part-sectional elevation of a portion of a braiding machine showing the new device applied thereto; Fig. 2, a plan view of the bottom of one of the lower supply-carriers showing the feeler-device controlled by the yarn from the lower supply cop; Fig. 3, a detail view of the feeler-device controlled by the yarn from the upper supply cop.

Referring to Fig. 1, the braiding machine here shown is similar in general respects to that described in my patent above referred to and therefore need not be described in detail. It comprises the essential elements of a main frame 2 provided with ball-bearings for the turrets or heads 3 and 4 which rotate thereon in opposite directions about the axis of the machine. The outer turret 4 is provided with overhanging brackets or supply-carriers 5 which support cop-holders 6 on which are carried the lower supply cops 7. The outer rim of the turret 4 is formed with a race or track 8 on which the upper supply-carriers 9 are supported with their runners 10 adapted to slide in the groove 11. The outer turret 4 rotates in one direction to

revolve the cop-holders 6, while the inner turret 3 rotates in the opposite direction and drives the supply-carriers 9 on the track 8. Suitable engaging means are provided between the turret 3 and carriers 9 to allow the yarns *y* from the lower supply cops 7 to pass over and under the upper carriers 9, and the yarns *x* lead up from the cops 12 and merge with the yarns *y* to form the fabric *b*.

The stopping-mechanism of the machine is controlled through a brake-ring 14 which is mounted on a flange 15 of the frame 2 and adapted to be moved rotatively about its axis to a slight extent to release the detent which controls the clutch-actuating devices. The rotative movement of the brake-ring 14 also acts to raise it bodily from its bearing on the flange 15 to force its beveled face 16 into contact with an oppositely beveled face 17 on the turret 4, and thereby a wedging action is effected which tends to raise the turret 4 against its bearing 18 on the turret 3. The three elements 14, 4 and 3 are thus carried into frictional engagement to exert a braking action to arrest the rotation of the two turrets. The particular arrangement of these means is fully described in my Patent No. 1,008,504, granted Nov. 14, 1911, and need not here be further described.

The brake-ring 14 is operated through the medium of arms or levers 20, spaced at intervals around its circumference and adapted to be engaged by feeler-devices on the turret 4. These latter are actuated by means controlled by the tension on the yarn *y* and *x* delivering from the supply cops 7 and 12, as later described. The arms 20 are pivoted at 21 on the flange 15 of the frame 2 and engage the ring 14 by means of screws 22 extending through slots in the arms. The upper ends of the arms 20 are formed with enlarged portions 23, bent at right-angles to the main portions and adapted to provide heads for engagement with the feeler devices. The exact structure and arrangement of the arms 20 will be more fully described in an application to be filed later, but for the present purpose it is sufficient to state that by swinging the arms on their pivots they act to pry the ring 14 rotatively on its bearing. This rotative movement of the ring releases the detent means of the clutch-actuating device to effect the stopping of the machine, as de-

- scribed in my Patent No. 1,008,504, granted Nov. 14, 1911, last referred to.
- The brackets 5 are formed with upwardly projecting lugs 24 having suitable slots in which are pivoted bell-crank levers 25. One arm 26 of the lever 25 reaches down to bring its end adjacent the head 23 on the arm 20, but this end is normally kept raised away from the latter by a coiled spring 27 held in a pocket 28 in the lug 24. The opposite arm 29 of the lever 25 extends upward with its end in close proximity to the deck of the carrier 9. Pivoted on the rim of the turret 4 is a bow-shaped lever 30 having a curved cam-face on its edge 32, see Fig. 3, and with its under side adapted to bear on the end of the arm 29 of the lever 25. When the lever 30 is depressed it acts on the lever 25 to move the arm 26 down into position to engage the head 23 on the arm 20. The lever 30 is moved through engagement with a drop-wire 31 which is normally suspended above the path of the lever by the tension on the yarn *x*. When the drop-wire 31 is released its lower end will engage the lever 30, as shown in Fig. 3, and riding over the curved edge 32 in the direction indicated by the arrow *d*, act to depress the lever 30 to tilt the lever 25.
- 30 The arrangement of the drop-wire 31 and its coacting devices will not be described in detail since they are not claimed herein, but form the subject matter of a separate application. It will be obvious, however, from the present showing that the falling of the drop-wire, when released by the breakage, exhaustion or hindrance to delivery of the yarn *x*, will act on the lever 30 to operate the feeler-device 25 which coacts with the arm 20 to stop the machine. The arm 20 is also adapted to be engaged by a feeler-device controlled by the tension on the yarn *y* delivering from the lower supply-cop 7, as now explained.
- 45 The cop-holder 6 is mounted on the bracket 5 to rotate with the cop as the latter unwinds the yarn and its rotation is controlled by a pawl or detent 33 adapted to engage the teeth 34 on the inside of the rim 50 of the base 35, see Fig. 2. The pawl 33 is normally held in engagement with the teeth by a spring 36 held in a pocket 37 in a lug 38 on the bracket 5. The release of the pawl to allow the cop-holder to turn is effected 55 through a tension arm 39 having a guide 40 through which the yarn draws. The arm 39 extends from a rocker-shaft or rod 41 which at its lower end is formed with a lever 42. The lever 42 has one arm 43 adapted to engage the side of the pawl 33 and another oppositely extending arm 44 to which is secured one end of a coiled spring 45. The opposite end of the spring 45 is fastened to a lever 46 which can be adjusted to vary the 60 amount of the spring's tension on the arm 44. Extending from the bottom of the bracket 5 is a stud or abutment 47, which engages the arm 44 and acts as a stop to limit its range of movement under action of the spring 45. When the yarn *y* is taken up by the braiding operation of passing it over or under the upper supply the draft on the yarn will swing the arm 39 in the direction indicated by the arrow *a*, Fig. 2. Such movement of the arm will rock the rod 41 and bring the arm 43 of the lever 42 against the pawl 33. This releases the pawl 33 from engagement with the teeth 34 and allows the cop-holder 6 to rotate to deliver a length of yarn as required. When the tension on the yarn *y* is relieved the arm 43 swings back under influence of the spring 45 to allow the pawl to again engage the teeth on the base of the cop-holder and the latter is thus prevented from further rotation. The spring 45 is adjusted according to the strength of the yarn and the character of the fabric to be produced, so as to normally hold the arm 43 just out of range of the pawl 33 until it is required to render a length of yarn from the cop. Should the yarn break, however, or the supply become exhausted, the arm 39 will be entirely released and the spring 45 acting on the arm 44 will swing the latter clear 95 back against the limiting stop 47. As the arm 44 swings back to its extreme position, as illustrated in Fig. 2, its extremity engages the end of a feeler-rod 48 which is adapted to coact with the arms 20 on the main frame of the machine as now described.
- The rod 48 extends parallel to the bottom of the bracket 5 and is mounted to slide in bearings in the lugs 49 and 50. The main portion of the rod 48 extends through a hole in the lug 49 with its end 51 projecting therefrom in position to engage the head 23 of the arm 20, see Fig. 1. At 52 the rod 48 is bent in an elbow and then extends at right angles thereto in the straight portion 53 which passes through a slot 54 in the lug 50, see Fig. 2. The rod is then bent back in a loop with its portion 55 extending through a hole 56 in the lug 50, and having its end bent down at 57 to provide a stop to prevent it from sliding out of its bearings. The weight of the rod 48 normally keeps it in a position with its end 51 out of range of the arms 20; when, however, the arm 39 is relieved of the tension of the yarn *y*, the arm 44 will swing back under action of its spring 45 and strike the end of the rod 48, thereby projecting the latter into position to engage the head of the arm 20 as the bracket 5 revolves about the axis of the machine. This engagement causes the operation of the stopping-mechanism as before described.
- To arrest the operation of the machine when the yarn catches on the cop, becomes 130

tangled, or fails to deliver freely from any other cause, I provide the following instrumentalities: Pivoted in a lug 60 on the under side of the bracket 5 is a lever 61, 5 preferably formed of wire, with one arm 62 reaching out to engage the feeler-rod 48. The end of the arm 62 is here shown as formed with a loop 63 which hooks around the elbow 52 so that the movement of the 10 arm will effect a corresponding movement of the feeler-rod. The lever 61 also has an arm 64, the end of which lies adjacent the pawl 33, see Fig. 2. Only a slight movement of the pawl 33 is required to release 15 its toe from the teeth on the cop-holder 6 and normally this movement does not affect the position of the arm 64 of the lever 61. Should the cop-holder be held from turning, however, after the pawl is released, as, 20 for instance by the snarling or tangling of the yarn, then the arm 39 will continue its movement in the direction indicated by the arrow *a*, under the abnormal tension on the yarn. This continued movement of the arm 25 39 causes the arm 44 to swing the pawl 33 a sufficient extent to engage the arm 64 of the lever 61 and thereby move the latter in the direction indicated by the arrow *c* to slide the feeler-rod 48 into position to engage the arm 20. The mechanism operates 30 in the same manner when a snarl or tangle occurs as the yarn leaves the cop. Any abnormal bunch or knot in the yarn will be prevented from passing through the loop 35 or guide 40 and the arm 39 will therefore be swung under the influence of the excessive tension in the direction indicated by the arrow *a* to cause the pawl 33 to move the lever 61 and slide the feeler rod to stop the 40 machine.

The operation of the whole mechanism is as follows: It will be understood that the 45 turret 4 rotates on the axis of the machine and carries the feeler-devices 25 and 48 around with it. Normally, when the yarns *x* and *y* are delivering from the supply cops 12 and 7 under tension, the lever 25 is maintained out of range of the arms 20 by the spring 27, and the feeler-rod 48 is also depressed out of range by the action of gravity. When the upper yarn *x* breaks, becomes exhausted, or fails to deliver properly the drop-wire 31 moves down into position to engage one of the levers 30. The levers 50 55 30 are spaced around the rim of the turret 4 and are equal in number to the levers 25 which correspond in number to the lower supply brackets 5. It will also be understood that there is the same number of upper supply-carriers which travel on the track of the turret 4 in the opposite direction to the latter's rotation. It is therefore obvious that when a drop-wire on one of the upper carriers falls it will almost instantly meet 55 with one of the levers 30 traveling in the

opposite direction, and, as before stated, as the wire 31 travels over the curved edge of the lever 30 the latter is depressed to the position illustrated by dash lines in Fig. 3. This tilts the lever 25 into position to meet 70 one of the arms 20, which are arranged around the frame of the machine, and the latter is rocked to pry the brake-ring 14 through a relatively slight rotative movement which, in turn, effects the action of 75 the stopping- and braking-mechanism. When a yarn *y* from the lower supply 7 breaks or is exhausted the lever 39 is released and the arm 44 swings back under the action of the spring 45 to project the 80 feeler-rod 48 into position to engage one of the arms 20. The rod 48 then coacts with the arm 20 in the same manner as the lever 25 to stop the machine. When the yarn *y* is hindered from delivering, or a 85 tangle obstructs the guide 40 on the arm 39, the latter is moved in the direction indicated by the arrow *a* and, through the arm 43 and pawl 33, the lever 61 is moved to project the 90 feeler-rod 48 into its operative position.

It will be seen that my invention provides a simple and efficient mechanism for operating the feeler-devices to coact with the stopping-mechanism when a yarn breaks or its delivery is impeded, and the new device 95 is particularly positive and quick in action, thus insuring prompt stopping of the machine upon failure of any one of the yarns.

Various modifications might be made in the structure and arrangement of the parts of the device without departing from the spirit and scope of the invention.

Therefore, without limiting myself to the precise construction shown and described, what I claim is:

1. In a braiding machine, the combination with a rotating turret, of supply-carriers revolved by said turret about the axis of the machine, stopping-mechanism to arrest the rotation of the turret, feeler-devices carried by the turret and adapted to be moved into position to cause the operation of the stopping-mechanism, tension-devices to control the delivery of the yarn from the supply-carriers, and means coöperating 110 with said tension-devices to cause the operation of the feeler-devices under abnormal tension on the yarn.

2. In a braiding machine, the combination with the rotating turrets, of supply-carriers revolved by said turrets about the axis of the machine, stopping-mechanism to arrest the rotation of the turrets, feeler-devices for causing the operation of the stopping-mechanism, tension-devices on the carriers for controlling the delivery of the yarn, and means coöperating therewith to actuate the feeler-devices upon relief or excess of tension on the yarn.

3. In a braiding machine, the combina- 130

tion with a plurality of supply-carriers for carrying the supply-cops of yarn, of means to revolve the supply-carriers about the axis of the machine, stopping-mechanism to arrest the movement of the supply-carriers, means to actuate the stopping-mechanism, feeler-devices carried by said supply-carriers and adapted to be thrown into position to cause the operation of the stopping-mechanism through their movement with the carriers, means to control the delivery of the yarn from the supply-carriers, and devices coöperating therewith to actuate the feeler-devices when the delivery of the yarn is impeded.

4. In a braiding machine, the combination with a plurality of supply-carriers for carrying the supply-cops of yarn, of means to revolve the supply-carriers about the axis of the machine, stopping-mechanism to arrest the movement of the supply-carriers, feeler-devices to cause the operation of the stopping-mechanism, tension-devices carried by the supply-carriers to control the delivery of the yarn therefrom, and means whereby said tension-devices act in one direction upon relief of tension and in the opposite direction upon excess of tension to move the feeler-devices to cause the operation of the stopping-mechanism.

5. In a braiding machine, the combination with a plurality of supply-carriers for carrying the supply-cops of yarn, of means to revolve the supply-carriers about the axis of the machine, stopping-mechanism to arrest the movement of the supply-carriers, feeler-devices to cause the operation of the stopping-mechanism, a rock-shaft on the supply-carrier, an arm on said shaft adapted to be moved from variations in tension on the yarn, a lever operated from said arm through the rock-shaft, a spring to control the movement of the arm and lever, and means intermediate the lever and feeler-device to cause the operation of the latter when the arm is moved against the action of the spring under abnormal tension on the yarn.

6. In a braiding-machine, the combination with the stopping-mechanism therefor, of means to operate the same, a feeler-device to actuate said means, a rotatable cop-holder for carrying the supply-cop, a detent to prevent the rotation of the cop-holder, means controlled by the tension on the yarn and movable to release said detent, and devices intermediate said means and the feeler-device to operate the latter when the movement of the tension controlled means is continued after the release of the detent.

7. In a braiding-machine, the combination with the stopping-mechanism therefor, of a feeler device for causing the operation of the same, a rotatable supply-holder for carrying the supply-cop, a detent to prevent the ro-

tation of the supply-holder, means controlled by the tension on the yarn to move said detent to release the cop-holder, and means operated by excessive movement of the detent to move the feeler-device to stop the machine.

8. In a braiding-machine, the combination with the stopping-mechanism therefor, of a feeler-device for causing the operation of the same, a rotatable supply-holder for carrying the supply-cop having a base formed with ratchet teeth, a pawl to engage said teeth to prevent the rotation of the supply-holder, means controlled by the tension on the yarn to move said pawl to disengage the teeth, and means operated by a continued movement of the pawl after its disengagement to operate the feeler-device.

9. In a braiding-machine, the combination with the stopping-mechanism therefor, of a feeler-device movable to cause the operation of the same, a rotatable supply-holder for carrying the supply-cop, a detent to prevent the rotation of the supply-holder, a lever operated by the tension on the yarn to release said detent, and a second lever adapted to move the feeler-device, said lever operated by the detent when the movement of the latter is continued after its release of the supply-holder.

10. In a braiding-machine, the combination with the stopping-mechanism therefor, of a feeler-device for causing the operation of the same, a rotatable supply-holder for carrying the supply-cop, a detent adapted to engage the supply-holder to prevent its rotation, a lever controlled by the tension on the yarn and movable in one direction to release the detent, said lever movable in the opposite direction to operate the feeler-device, and a second lever operated by the continued movement of the detent after its release of the supply-holder to actuate the feeler-device.

11. In a braiding-machine, the combination with a bracket, of a rotatable supply-holder mounted thereon, a detent to control the rotation of the supply-holder, a lever adapted to be moved in one direction to release the detent, a feeler-rod adapted to be engaged by the lever when the latter is moved in the opposite direction, and a second lever engaged by the detent to move the feeler-rod when the movement of said detent is continued beyond the releasing of the supply-holder.

12. In a braiding-machine, the combination with a rotatable supply-holder, of a detent for controlling the rotation of the same, a lever controlled by the tension on the yarn and movable in one direction to release the detent, a spring to move the lever in the opposite direction, a feeler-device operated by the lever when moved by the spring, and means to operate the feeler-device when the

movement of the detent is continued after the release of the supply-holder.

13. In a braiding-machine, the combination with the stopping-mechanism therefor, of a rockable arm 20 for actuating the same, a pivoted lever 25 adapted to be tilted into position to engage and move said arm, a curved lever 30 engaging the lever 25, and a drop-wire 31 arranged to ride over the 10 curved edge of said lever 30 to depress the latter to tilt the lever 25.

14. In a braiding-machine, the combination with the stopping-mechanism therefor, of a supply-carrier 9 having a drop-wire 31 controlled by the tension on the yarn, a 15 feeler-lever 25 for causing the operation of the stopping-mechanism, and a curved lever 30 arranged to actuate said feeler-lever and adapted to be depressed by the engagement 20 of the drop-wire riding over its curved edge.

15. In a braiding-machine, the combina-

tion with a tilting feeler-lever 25, of a pivoted lever 30 adapted to engage the lever 25 and formed with a cam face 32, a supply-carrier 9 for the supply cop, and a drop-wire 31 on said carrier adapted to ride over the cam face 32 to depress the lever 30 and tilt the lever 25.

16. In a braiding-machine, the combination with the stopping mechanism therefor, 30 of a feeler-lever 25 for actuating the same, a pivoted lever 30 formed with a cam face 32, and means adapted to ride over said cam face to depress the lever 30 to move the lever 25.

In testimony whereof I affix my signature in presence of two witnesses.

SIMON W. WARDWELL.
